UNITED STATES PATENT OFFICE.

EBBERT A. JONES, OF DANVILLE, VIRGINIA, ASSIGNOR, BY MESNE ASSIGNMENTS, TO JONES-BOARDMAN BUNCH BUILDER CORPORATION, OF BALTIMORE, MARYLAND, A CORPORATION OF MARYLAND.

SPINNING MACHINE.

1,407,754.

Specification of Letters Patent. Patented Feb. 28, 1922.

Application filed June 20, 1918. Serial No. 241,023.

To all whom it may concern:

Be it known that I, EBBERT A. JONES, a citizen of the United States, and residing at Danville, Pittsylvania County, State of Virginia, have invented certain new and useful improvements in Spinning Machines, of which the following is a specification.

This invention relates to mechanism by which yarn is laid and wound upon a rotating bobbin or yarn receiver. It has particular reference to the mechanism which builds a small body of yarn at the lower portion of the bobbin or spindle called the bunch and then builds a main body of yarn on the spindle. The necessity for building the bunch is well known in the art since it acts through the automatic feeler of certain machines to prevent winding off all of the yarn on the bobbin which would cause a defect in the fabric and produce what is called a second. Much difficulty has been experienced in producing a machine which will build an entirely satisfactory bunch and a satisfactory main winding, and this seems to have been due to the fact that so many different elements enter into consideration. The yarn constituting the bunch is not drawn off in use but goes to waste and therefore from the standpoint of economy it is essential that the amount of yarn used in the bunch be reduced to a minimum. It is essential, however, that the bunch have a certain thickness in order to operate the feeler. It is also essential that the bunch be so wound as to be firm and to prevent tangling or breaking of the yarn, and it is desirable that it shall be placed low on the spindle or bobbin so as to permit as much yarn as possible to be placed on the spindle by the main winding. The character of the bunch, as well as of the main winding, depends largely upon the length of the traverse or strokes of the builder arm during its formation and upon the gain of the traverse or the pick at each stroke of the builder. I have found that in building a short, thick and firm bunch and then the main winding it is necessary that the traverse and the pick or gain shall be considerably less in building the bunch than in the main winding, but that the gain or pick in building the main winding should not be as much greater than the pick or gain in forming the bunch as is the traverse or strokes of the builder arm

in building the main winding greater than 55 the traverse or stroke in building the bunch. In other words, the increase in the gain or pick must not correspond to the increase in the stroke or traverse in changing from the bunch to the main winding. If the increase in the pick corresponds to the increase in the stroke or traverse it will follow either that the traverse in forming the bunch is too long to form a short or satisfactory bunch or, the gain in the main winding will 60 be too great, and the result will be that the yarn will be spread out too thin in the main winding and the proper main winding will not be produced.

The present invention is designed to cause 70 the building of the bunch at as low a point as desired, as thick, as firm and as short as desired, preventing tangling and breaking while avoiding waste and then automatically causing the building of a main winding with 75 a predetermined traverse and a predetermined pick or gain to give to the main winding the desired thickness and taper.

Some of the features of this invention relating to the pick mechanism are disclosed 80 but not claimed in my prior Patent Number 1,206,542 November 28, 1916, where the claims related particularly to the mechanism there disclosed for changing the traverse in forming the bunch. The broader 85 ideas relating to this matter may, therefore, be said in a sense to be divided out of my patent although the present construction includes improvements on those ideas. The present invention also includes improvements 90 on the traverse controlling mechanism of my prior patent. The novel features of the invention will be apparent from the following description taken in connection with the drawings.

95 In the drawings:-

Figure 1 is an end view of a spinning machine having the present invention applied thereto;

Figure 2 is an enlarged fragmentary end 100 view of the builder arm and operating connections illustrating particularly the pick mechanism;

Figure 3 is a top plan view of the builder arm and its attachments;

Figure 4 is a side view of the builder arm and attachments;

Figure 5 is a section on the line 5-5

of Figure 3 looking towards the builder arm;

Figure 6 is a view similar to Figure 4 but taken from the opposite side;

5 Figure 7 is a view similar to Figure 4 showing the bunch roller in inoperative position;

10 Figure 8 is a side view of the builder arm and cams in the position occupied in building the bunch;

Figure 9 is a diagrammatic view showing the two cams and their relations to the rollers operated thereby during the building of the bunch;

15 Figure 10 is an enlarged cross section on the line 10—10 of Figure 4 looking towards the end of the builder arm with the pick mechanism in position to build the bunch; and

20 Figure 11 is a view corresponding to Figure 10 but showing the pick mechanism in position for building the main winding.

My invention is applicable to spinning machines of well known types and while it 25 is not necessary to go into a detailed explanation of those machines in order to enable one skilled in the art to understand the invention, it is necessary to have in mind certain well known features of those machines. As shown in Figure 1 the machine in which the invention is applied embodies a main frame construction 10 and a cross frame 11 carrying a series of ordinary rotating spindles or bobbins 12 in the usual manner. A ring rail 13 is adapted to reciprocate up and down the bobbins in order to guide the yarn properly in winding and this ring rail is given its up and down movement by the push rod 14 sliding through the 30 bearings 15, 16 on the parts of the main frame. The lower end of the push rod 14 rests on the horizontal arm of the bell crank lever 17 which is pivoted at 18 in a frame 19 secured to a fixed part of the machine. The 40 vertical arm of the lever 17 is connected to a cable 20 which is constantly pulled towards the left in Figure 1 by any well known means such as a roller and weight. The tendency of the bell crank lever 17 45 under the influence of the cable 20 is therefore to raise the ring rail and the tendency of the ring rail is to descend by gravity except when pushed up by the push rod. The amount which the ring rail will be raised is 50 limited by mechanism including the pivoted segment 21 to which the cable 20 is secured and a chain 22 which passes over the roller 23 secured to a fixed part of the frame and down to the builder arm 24. The builder 55 arm is pivoted at one end to a fixed part of the frame and the pull on the chain 22 through the cable 20 tends to raise that builder arm but it is held down by the contact of a roller carried by it with the 60 operating cam. The main cam which en-

gages and holds down the builder arm, as is customary in machines of this kind, is shown at 25 mounted on the end of the rotating shaft 26 which is turned by any suitable means such as the pulleys 27. A roller 28 70 in fixed position on the side of the builder arm engages the periphery of this cam and the rotation of the cam therefore makes the builder arm oscillate vertically thus pulling on the chain 22 and turning the bell crank 75 17 to lower the ring rail 13. The extent of the reciprocation or traverse is controlled by the shape of the cam 25. In addition to the above mentioned features the builder arm is also provided with mechanism for causing 80 the lever 17 to turn on its pivot gradually and progressively raising the ring rail 13 along the spindle without changing or effecting the traverse or length of stroke of the ring rail. This is done by the pick mechanism including a ratchet wheel 29 and a pawl 30. The ratchet wheel is secured to the end of a rotary shaft 31 mounted in bearings 32, 33 on the builder arm and carrying the worm gear 34. A segmental sliding plate 35 having teeth 36 on its edge engaging the worm gear 34 is moved by the rotation of the shaft 31. The plate 35 carries a roller 37 over which the chain 22 passes after it leaves the roller 23. The end of the chain 95 22 is secured at a fixed point 38 to the builder arm so that a movement of the sliding plate 35 with its roller 37 to the right as shown in Figure 6 will have the practical effect of lengthening the chain connection 22 between 100 the segment 21 and the builder arm thus permitting the bell crank lever 17 to turn to the left raising the ring rail. The particular construction by which the pawl and ratchet pick mechanism rotate the shaft 31 105 and cause the elevation or gain in the transverse will be described in detail later and it is sufficient now to say that it is operated by the reciprocation of the builder arm and this broadly considered was all old in the 110 art.

According to my present invention I make use of a supplemental or bunch cam 39 in addition to the usual cam 25 and mount it on the same shaft 26 with the main cam. I 115 also mount on the builder arm 24 a supplemental roller 48 to cooperate with the supplemental cam 39 in building the bunch. The roller 48 is not in a fixed operative position but is adjustable and may be held in 120 operative position during the building of the bunch and may then be released or rendered inoperative. It is located in the same vertical plane with the roller 28 but at a higher lever, as shown particularly in Figures 2 and 4. The purpose of this supplemental roller and supplemental cam is to cut in two the effective action of the main cam 25 in reciprocating the builder arm thus cutting in two the traverse of the ring rail dur- 125 130

ing the building of the bunch. The two cams 25 and 29 are so arranged that when the roller 48 is in operative position they will alternately engage their rollers at each 5 revolution of the cam shaft; the high points of each cam only engaging its roller. This action will be apparent from the diagrammatic illustration in Figure 9 from which it will be seen that as the roller 28 rides over the high parts of the cam 25 it will lift the roller 48 out of contact with the supplemental cam 39 and conversely when the high parts of the supplemental cam 39 engage the roller 48 the roller 28 will be lifted out of 10 contact with the main cam 25. For instance, starting with the roller 48 in contact with the supplemental cam 39 at *a* with the cam moving in the direction indicated by the arrow, the roller will ride over the surface of cam 39 to the point marked *b* lifting the roller 28 out of contact with the main cam 25 at *c* and allowing it to come in contact with the main cam again at *d*. The roller 28 by its contact with the main cam will 15 then lift the roller 48 out of contact with the supplemental cam 39 and the roller 28 will ride over the surface of the main cam to the point marked *e*. At that point the roller 48 will again come in contact with the supplemental cam 39 at *f* and the operation will 20 thus continue around the periphery of the cams, the builder arm being depressed alternately by the high portions of the two cams. This results in shortening the upward movement of the builder arm which it would normally have under the influence of the main cam 25 only and multiplies the number of reciprocations of the builder arm and consequently of the ring rail during each revolution of the cam shaft. This gives a short substantially uniform traverse during the building of the bunch and the connections through the chain 22 may be so adjusted that when the roller 28 at the beginning of the 25 operation is at the highest point of the cam 25 the ring rail will be at the bottom of the spindle 12 or at the point where it is desired to commence building the bunch. The ring rail will rise from that point the definite amount above indicated as the points of the cams engage the rollers thus producing the short traverse for the bunch. The roller 48 is held in stationary position on the builder arm throughout the building of the bunch and is then automatically rendered 30 inoperative so as to throw out of operation the supplemental cam 39 and permit the main winding to proceed under the influence of the main cam 25 alone. The roller 28 will then follow the surface of the main cam 25 both in the low parts and in the high parts thus causing a considerably longer stroke of the builder arm and a longer traverse of the ring rail.

65 The mechanism for causing a gain of the

traverse as above indicated includes the rotary shaft 31 mounted on the builder arm and carrying the worm gear 34 which meshes with teeth in the sliding segmental plate 35. The shaft 31 is given a slight rotary movement at each reciprocation of the builder arm and thus the plate 35 is given a slight longitudinal or sliding movement. The effect of this is to so move the roller 37 as to allow greater slack in the chain 22 thus permitting the bell crank lever 17 to turn and gradually feed or elevate the ring rail. The mechanism by which the shaft 31 is turned includes the ratchet wheel 29 rigidly secured to its end. A pawl 30 is loosely pivoted at 49 to the end of a plate 50 which is loosely and rotatively mounted on the shaft 31. This pawl 30 has below its pivot a sharp pointed end 51 which is adapted to engage the teeth of the ratchet wheel, and the pawl has an outwardly extending straight projection 52, the weight of which tends to keep the point 51 in contact with the ratchet teeth. It will be understood that the pawl will ride freely over the teeth when moved in a counterclockwise direction, as shown in Figure 2. The plate 50 has on its projection end diagrammatically opposite the pawl a weight 53 which normally tends to turn the plate 50 so as to move the pawl counterclockwise to 90 its upper position. Secured to a fixed portion of the main frame of the machine there is a stop 54 in the path of the projecting end 52 of the pawl so that as the builder arm is elevated in its stroke the end 52 of the pawl will be engaged by the stop 54 and the plate 50 will thereby be swung around on its pivot on the shaft 31 and the ratchet wheel 29 will be turned an amount corresponding to the amount of upward movement of the builder arm after the point 52 strikes the stop. In order to be able to regulate the time in the upward movement of the builder arm when the pawl engages the stop 54, a plate 55 is rotatively mounted on the shaft 31 close against the plate 50 and it carries a projecting pin 56 which is adapted to make contact with the side of the builder arm 24 at a certain point in its rotary movement on the shaft. This plate 55 is secured 105 to the plate 50 by an adjustable bolt 57 or other suitable means passing through the slot 58. The relation of the plates 50 and 55 may therefore be changed and they may be secured together in the position desired. In 110 this way when the stop 56 strikes the side of the builder arm it limits the upward movement of the pawl 30 and by controlling its position determines at what point in the upward movement of the builder arm it will 115 come into operation by contact with the stop 54. In building the bunch the parts may be so set as to make the pawl engage the ratchet wheel during a sufficient amount of the upward stroke to cause the particular 120

amount of gain or pick necessary in forming the bunch. The stroke of the builder arm in building the bunch is comparatively short and consequently the normal gain would be 5 comparatively small but as above stated it may be regulated and thus I am enabled to build a short, thick, bunch with a slight gain at each stroke at the bottom of the spindle.

When the supplemental cam 39 is thrown 10 out of operation at the end of the building of the bunch and when the builder arm thereupon commences to make the long stroke for the main winding the result would naturally follow that the long 15 stroke after the pawl 30 comes in contact with the stop 54 would cause a correspondingly greater turning movement for the ratchet wheel 29 and its shaft 31 and consequently a correspondingly greater gain in 20 the traverse. Such a correspondingly greater gain, however, would make the conical layers of yarn on the spindle spread out too much thus not making a winding of the proper thickness and taper. According to 25 my invention, therefore, I have provided mechanism for interfering with or cutting in two the normal action of the pick mechanism when the change is made from the bunch winding to the main winding. This 30 includes mechanism connected with the supplemental roller 48 and which is brought into operation when the roller 48 is disabled or thrown out of operation at the end of building the bunch.

35 As shown particularly in Figure 4, the roller 48 for the supplemental cam is carried by a bell crank lever 59 pivoted at 60 to a member 61 secured on top of the builder arm 24 by the bolts 62. In building the 40 bunch the bell crank lever 59 and its roller 48 are held in the position shown in Figure 4 by a latch or pivoted lock 63 mounted on the pivot 64 secured to the builder arm. One arm of the bell crank lever rests on 45 one end of this latch 63 whereas the other end of the latch 63 has projecting from it a pin 65 which as seen in Figure 6 rides in a slot 66 in the sliding plate 35. The engagement of the pin 65 with the slot 66 holds the latch 63 in position and therefore 50 holds the roller 48 in operative position. When, however, the pick mechanism has moved the plate 35 a sufficient distance in causing the gain of the traverse the plate 55 will finally pass beyond the point where the pin 65 can engage the slot and thereupon the latch 63 will be free to turn on its pivot 64. The weight of the mechanism bearing on the roller 48 will then suddenly turn 60 the latch 63 and also the bell crank lever 59 throwing the roller 48 out of operation. In the construction shown particularly in Figures 4 and 7 I have illustrated a pivoted 65 stop or block of metal 67 pivoted at 68 to the builder arm near its end and near the

ratchet wheel 29 and pick mechanism. That pivoted stop is connected by an adjustable link mechanism 69 to one arm of the bell crank lever 59 so that when the bell crank lever is turned to lower the roller 48 out 70 of operative position it at the same time turns the stop 67 into vertical position. When in vertical position the lower end of the stop 67 is above the pin 56 which, as heretofore explained, controls the amount 75 of free movement of the pawl 30 around the ratchet wheel 29. The effect of interposing this stop 67 in the path of the movement of the pin 56 is therefore to cut short 80 the picking action of the pawl and to delay 85 the time in the upward movement of the builder arm when the pawl 30 comes in contact with the stop 54. This automatically cuts in two the normal pick and prevents the amount of gain from increasing 90 in the same proportion that the stroke of the builder arm has increased. In the subsequent operation of the device in building the main winding the stop 67 remains in 95 position in the path of the pin 56, thus continuously interfering with or cutting in two the pick. This construction enables me to so regulate the gain in the traverse in forming the main winding as to produce the best form of winding and permits me to 100 use a different pick in the bunch winding so as to get the best form of winding for the purpose of the bunch. It furthermore permits me to start the bunch at the bottom without making the gain unduly long on 105 the main winding since I can make the picking action commence at any period of the upward stroke of the builder arm desired. It will be observed that the pin 65 is adjustable in the slot 70 so as to regulate 110 the time when the latch 63 will be released and it is also to be noted that the connection between the stop 67 and the bell crank lever 59 is adjustable to regulate the action of that stop.

110 My invention has a distinct advantage in that it is not only applicable to new machines but can be applied with little trouble or expense to many machines now in general use. It will be observed that the 115 builder arm 24 is pivotally mounted at 71 to a fixed part of the frame and oscillates in a vertical plane from that pivot under the influence of the pull exercised by the chain 22 and the action of the cams 28 120 and 48. The action of the apparatus in building a bunch with a uniform movement to the builder arm and a short substantially uniform traverse a small gain results in causing the rail to dwell longer at the bottom of the quill during the formation of the bunch and thus gives the operator time within which to piece up broken ends before going on the regular or long stroke.

125 While I have illustrated a preferred em- 130

bodiment of my invention it will be understood that it is not limited to that particular form since various changes may be made in the construction without departing 5 from its principles.

Having thus described the invention what is claimed as new and desired to be secured by Letters Patent is:—

1. In a spinning machine, a builder motion including a reciprocating builder arm, means controlled thereby to effect the formation of a preliminary or bunch winding with a short traverse throughout the building of the bunch and a succeeding main winding with a much longer traverse from beginning to end, pick mechanism for causing a gain of the traverse at each reciprocation and automatic means for delaying or cutting in two the normal effective action of 20 said pick mechanism on the first long traverse and thereafter.
2. In a spinning machine, a builder motion including a reciprocating builder arm and controlling means causing it to have a short uniform stroke during the formation of a preliminary or bunch winding with a short traverse and then a longer uniform stroke during the formation of the main winding with a long traverse, pick mechanism 25 carried by said builder arm causing a gain of the traverse at each reciprocation the amount of the gain being normally in proportion to the length of the builder arm stroke, and means for automatically delaying or cutting in two the effective action of 30 said pick mechanism as the stroke of the builder arm gets longer whereby the amount of the pick will not increase in proportion to the increase in the length of stroke.
3. In a spinning machine, a builder motion including a reciprocating builder arm, means controlled thereby to effect the formation of a preliminary or bunch winding with a short traverse throughout the building of 40 the bunch and a succeeding main winding with a much longer traverse from beginning to end, means for causing a gain of the traverse at each reciprocation including a pawl and ratchet, means tending to cause said 45 pawl to freely move over said ratchet in one direction, a stop for limiting such free movement, fixed means on said machine in the path of said pawl and against which it will strike on a reciprocation of the builder arm 50 thereby causing it to effectively engage and move said ratchet in proportion to the subsequent movement of said arm, a movable member adapted to be brought into position to limit the free movement of said pawl over 55 the ratchet thereby delaying its engagement with the fixed means on the machine in its path when the builder arm reciprocates rendering the amount of pick less than it would otherwise be and means for automatically 60 bringing said movable member into opera-
6. In a spinning machine, a builder motion including a reciprocating builder arm, means for giving said arm a short uniform stroke to effect the formation of a preliminary or bunch winding with a short traverse and then a long uniform stroke to effect the 65 formation of a succeeding main winding with a long traverse, pick mechanism controlled by the reciprocations of said builder arm for causing a gain of the traverse, means for causing said pick mechanism to come into action at a predetermined point in the movement of said arm during the short stroke in building the bunch and means for causing said pick to come into action at a later point in the movement of the said 70 arm on the beginning of the long stroke in building the main winding.
7. In a spinning machine, a builder motion including a reciprocating builder arm, means for giving said arm short uniform 75

traverse position on the first long traverse and thereafter.

4. In a spinning machine, a builder motion including a reciprocating builder arm, means controlled thereby to effect the formation of 70 a preliminary or bunch winding with a short traverse throughout the building of the bunch and a succeeding main winding with a much longer traverse from beginning to end, means on said builder arm for causing 75 and controlling the gain of the traverse, including a rotary shaft, a ratchet wheel secured to said shaft, a pawl adapted to engage said ratchet, a member rotatively supported on said shaft carrying said pawl so 80 overbalanced as to tend to raise said pawl without effectively engaging the ratchet, a fixed stop on said member cooperating with a fixed part of the builder arm mechanism to limit the amount that the overbalanced 85 member can normally raise said pawl, a movable member carried by said builder arm adapted to move into the path of said stop thus cutting in two the normal upward movement of the rotatively supported member 90 and pawl and a fixed member on the machine adapted in the path of said pawl to be engaged by and effectively operate said pawl to turn said ratchet wheel as the builder arm reciprocates.

5. In a spinning machine, a builder motion including a reciprocating builder arm, means controlled thereby to effect the formation of a preliminary or bunch winding with a short traverse to build the bunch, 100 and a succeeding main winding with a long traverse, means for automatically and suddenly changing from the short traverse to the long traverse, pick mechanism controlled by and operating normally in accordance 105 with the reciprocations of said builder arm to cause a gain of the traverse and automatic means for partially disabling said pick mechanism during the long traverse.

6. In a spinning machine, a builder motion including a reciprocating builder arm, means for giving said arm a short uniform stroke to effect the formation of a preliminary or bunch winding with a short traverse and then a long uniform stroke to effect the 115 formation of a succeeding main winding with a long traverse, pick mechanism controlled by the reciprocations of said builder arm for causing a gain of the traverse, means for causing said pick mechanism to 120 come into action at a predetermined point in the movement of said arm during the short stroke in building the bunch and means for causing said pick to come into action at a later point in the movement of the said 125 arm on the beginning of the long stroke in building the main winding.

7. In a spinning machine, a builder motion including a reciprocating builder arm, means for giving said arm short uniform 130

reciprocations to effect the formation of a preliminary or bunch winding with a short traverse and means for then giving it long uniform reciprocations to form a main winding 5 with a long uniform traverse, pick mechanism controlled by the movement of said builder arm to cause a uniform gain of the traverse during the building of the bunch, automatic means for so interfering with the normal 10 action or timing of the pick mechanism on the change to the long traverse and throughout the formation of the main winding as to cause a uniform gain during the main winding greater than that in the bunch 15 winding but less than would be normally caused by the greater movement of the arm on the long traverse.

8. In a spinning machine, a builder motion including a reciprocating builder arm, 20 means for causing said arm to have a uniform short stroke throughout the building of the bunch and a long uniform stroke in subsequently building the main winding, means controlled by the builder arm to 25 effect the formation of a preliminary or bunch winding with a short traverse and a succeeding main winding with a long traverse, means for suddenly and automatically shifting from the short stroke to the long 30 stroke, pick mechanism for causing a gain of the traverse at each reciprocation and means controlled by said shifting means to cut in two and thereafter limit the normal effective action of said pick mechanism when 35 changing to the long traverse.

9. In a spinning machine, a builder motion including a reciprocating builder arm, means for causing said arm to have a uniform short stroke throughout the building 40 of the bunch and a long uniform stroke in subsequently building the main winding, means controlled by the builder arm to effect the formation of a preliminary or bunch winding with a short traverse and a 45 succeeding main winding with a long traverse, means for suddenly and automatically shifting from the short stroke to the long stroke, pick mechanism controlled by the movement of said builder arm to cause a 50 uniform gain of the traverse during the building of the bunch, automatic means controlled by said shifting means for so interfering with the action of the pick mechanism on the change to the long main winding 55 traverse as to prevent an increase in gain corresponding to the increase in the length of the traverse and to maintain a uniform gain during the main winding.

10. In a spinning machine, a power shaft, 60 a main cam carried by said power shaft, an auxiliary cam carried by said power shaft, a builder arm, a bell crank lever, a roller carried by said bell crank lever, and arranged to be engaged by said auxiliary 65 cam, a roller carried by said builder arm

and arranged to be engaged by said main cam, means for holding said bell crank lever with its roller in fixed operative position on said builder arm, and means brought into play by a predetermined number of reciprocations of said builder arm for suddenly releasing said bell crank lever and rendering its roller inoperative. 70

11. In a spinning machine, a power shaft, a main cam carried by said shaft, an auxiliary cam carried by said shaft, a builder arm, a roller carried by said builder arm arranged to be engaged by said main cam, an adjustable roller carried by said builder arm arranged when in one position of adjustment to be engaged by said auxiliary cam at an intermediate stage of the normal upward movement of the builder arm, means for holding said adjustable roller in a fixed operative position on the builder arm whereby it will shorten the effective stroke of the main cam, and means for automatically rendering said adjustable roller inoperative after a predetermined number of reciprocations of said builder arm. 80 85 90

12. In a spinning machine, a power shaft, a main cam carried by said shaft, an auxiliary cam carried by said shaft, a builder arm, a roller carried by said builder arm arranged to be engaged by said cam, an adjustable roller carried by said builder arm arranged when in one position of adjustment to be engaged by said auxiliary cam, a stop for holding said adjustable roller in fixed operative position, and means for automatically releasing said adjustable roller from the influence of said stop after a predetermined number of reciprocations of said builder arm. 95 100

13. In a spinning machine, a power shaft, 105 a main cam carried by said shaft, an auxiliary cam carried by said shaft, a builder arm, a roller carried by said builder arm arranged to be engaged by said main cam, a second roller so mounted as to be carried by 110 and move with said builder arm and arranged to be engaged by said auxiliary cam, the said rollers and cams being so arranged that each roller will be alternately engaged by the high parts of its cam during each 115 revolution of the power shaft, thus cutting in two the normal movement which the builder arm would have under the influence of the main cam alone and doubling the number of reciprocations of the builder arm for 120 each revolution of the cam shaft, the said reciprocations in building the bunch being substantially uniform in length, and means operated by the reciprocation of the builder arm to render the roller engaged by the 125 auxiliary cam inoperative after a predetermined number of reciprocations of the builder arm.

14. In a spinning machine, a power shaft, 130 a main cam carried by said power shaft,

- an auxiliary cam carried by said power shaft, a builder arm, a bell crank lever, a roller carried by said bell crank lever, and arranged to be engaged by said auxiliary cam, 5 a roller carried by said builder arm and arranged to be engaged by said main cam, a catch member for holding said crank lever and roller in fixed operative position, pick mechanism for causing a gain in the traverse, 10 and means operated through said pick mechanism for releasing said catch and rendering said roller inoperative after a predetermined number of picks.
15. In a spinning machine, a builder motion including a reciprocating builder arm and controlling means causing it to have a short stroke during the formation of a pre-
- liminary or bunch winding with a short traverse and then a longer stroke during the formation of the main winding with a long 20 uniform traverse, pick mechanism carried by said builder arm causing a gain of the traverse at each reciprocation the amount of the gain being normally in proportion to the length of the builder arm stroke, and 25 means for automatically delaying or cutting in two the effective action of said pick mechanism on the first long stroke and thereafter so that its effective action will be only slightly greater or longer on each long stroke 30 than it had been on any of the bunch building strokes.

In testimony whereof I affix my signature.
EBBERT A. JONES.
